UNITED STATES PATENT OFFICE.

GEORGE S. GRAY, OF CAPRON, OKLAHOMA.

DESIGN FOR A GRAVE-DECORATION CHEST.

Application filed April 2, 1928. Serial No. 26,101. Term of patent 7 years.

To all whom it may concern:

Be it known that I, GEORGE S. GRAY, a citizen of the United States, residing at Capron, in the county of Woods and State of Oklahoma, have invented a new, original, and ornamental Design for a Grave-Decoration Chest, of which the following is a specification, reference being had to the accompanying drawing, forming part thereof.

I claim:

The ornamental design for a grave decoration chest, as shown.

GEORGE S. GRAY.
